JOHN F. O'CONNOR, OF CHICAGO, ILLINOIS, ASSIGNOR TO W. H. MINER, INC., OF CHICAGO, ILLINOIS, A CORPORATION OF DELAWARE.

BUFFING MECHANISM.

Application filed March 31, 1927. Serial No. 179,364.

This invention relates to buffing mechanisms.

An object of this invention is to provide a buffing mechanism for a railway car, comprising a housing enclosing all of the working parts thereto, the working parts including a main spring resistance, a friction producing system, and a yieldably mounted buffer head, the latter under the influence of 5 lighter shocks being movable inwardly against relatively light spring resistance without operation of the friction producing system, and under heavier shocks being movable an additional distance to effect operation of the friction system and main spring 10 resistance.

Another object of the invention is to provide a buffing mechanism of this character in which a follower is associated with the 20 main spring resistance, and the friction system of which includes friction shoes which bear upon the follower and co-operate with a wedge, together with preliminary springs, the inner ends of which bear upon the 25 wedge and friction shoes and the outer ends of which bear upon the buffer head.

A further object of the invention is to provide a buffer of this type in which the housing is of fabricated construction comprising 30 channel members secured together with the flanges thereof disposed in spaced relation to form guide-ways for moving parts of the mechanism.

A still further object of the invention is to provide in a buffer of this type means for 35 securing the channel members together, including spacing and securing elements at front and rear, the former of which serves to limit outward movement of the buffer head, and the latter of which provides an abutting wall for the rear ends of the springs 40 forming the main spring resistance, in conjunction with an intermediate spacing and securing casing which co-operates with the channel members and provides an anchorage 45 and enclosing means for the members of the friction system.

Still another object of the invention is to provide wedge members having projecting 50 bosses thereon adapted to extend through suitable openings in the reinforcing casing and the webs of the channel members, whereby the wedge members are detachably an-

chored against longitudinal movement with reference to the buffer housing. 55

Other and further objects of the invention will more clearly appear from the description and claims hereinafter following.

In the drawings forming part of this specification, Figure 1 is a vertical longitudinal 60 sectional view taken centrally through the end platform of a railway car and showing the invention applied thereto. Figure 2 is a top plan view of the buffing mechanism detached from the car platform, and showing 65 the disposition of the various parts of the buffing mechanism in dotted lines. Figure 3 is a front elevation of the buffing mechanism. Figure 4 is a longitudinal vertical 70 sectional view of the invention corresponding substantially to line 4-4 of Figure 2. And Figure 5 is a transverse sectional view of the buffer corresponding substantially to line 5-5 of Figure 4.

As shown in the drawings, 10 denotes the 75 end platform of a passenger car provided with a central pocket 11 for the reception of a buffing mechanism indicated broadly by the numeral 12, the buffing mechanism being maintained in position by means of a bar 13 80 extending transversely across the bottom of the pocket 11 and connected to portions of the under-frame. The usual center stem member is indicated by the numeral 14, the inner 85 end of which co-acts with the buffing mechanism 12 while the outer end thereof co-acts with the buffing platform 15, which is supported in position by the usual side stems not shown.

The buffer proper comprises a pair of oppositely disposed channel members 16-16, 90 the webs of which form the top and bottom walls of the buffer housing, while the side walls of the housing are formed by the adjacent flanges 17-17 of the channel members 95 16-16, the channel members being secured together in a manner hereinafter described so as to space the adjacent ends of the flanges 17-17 to provide a guide-way 18 at each side of the housing. 100

The rear ends of the channel bars 16-16 are secured together and held in spaced relation by means of a rectangular member 19 inserted between the webs and flanges of the channel members and held in position by 105 means of a plurality of rivets indicated at

20 which extend through the webs of the channel members and the end member 19. The inner surface of the end member is provided with arcuate projections 21—21 which form seats for the springs forming a main spring resistance as hereinafter referred to. The forward ends of the channel members 16—16 are secured together by transversely spaced pairs of rivets 22—22, the rivets of each pair being surrounded by spacing thimbles 23 connected by a web portion.

Intermediate the ends of the channel member 16—16 is a combined spacing and securing shell 24, which encloses the friction system hereinafter described. The shell 24 comprises side walls 25—25 spaced inwardly from the flanges 17—17 at each side of the mechanism, as best shown in Figure 5, and top and bottom walls 26—26, each of the latter being provided with oppositely extending flanges 27—27 which are riveted to the webs of the channel members 16—16 by rivets 28—28, thereby securely connecting the channel members 16—16 together at an intermediate point, and maintaining the same in properly spaced relation.

Each of the top and bottom walls 26—26 at a central point is provided with an opening 29 which registers with a corresponding opening 30 in the adjacent web of one of the channel members 16—16, each pair of openings being adapted for the reception of a boss 31 formed integrally with each of the liners 32—32. The liners 32—32 fit against the top and bottom walls of the shell 24 and each has on its outer surface a friction surface 33, the opposed friction surfaces preferably converging inwardly of the mechanism. The forward ends of the liners 32—32 fit behind shoulders 34—34 formed upon the inner surface of the shell 24. Cooperating with the wedge faces of the wedge members 32—32 are top and bottom friction shoes 35—35 of like construction, each of the shoes having an outer friction surface 36 co-acting with the friction surface 33 of one of the liners 32—32, and having a wedge face 37 on the inner side co-operating with a centrally disposed wedge 38. At their rear ends the friction shoes 35—35 bear upon lugs formed on a spring follower 39 which is limited in its forward movement by the shell 24, and which is movable rearwardly against the resistance offered by the springs 40—40 which provide the main spring resistance of the mechanism, the rear ends of the springs 40—40 being disposed in the arcuate seats 21—21.

The wedge 38 is provided with a forwardly extending projection 41 adapted to be engaged by a post 42 formed upon the buffer head 43 of the mechanism. The head 43 of the mechanism comprises a forward wall the side portions of which are cut-out as indicated at 44—44, and the walls defining the cut-out portions engage the thimbles 23—23

at the forward end of the housing which limits forward movement of the buffer head 43. The side walls of the buffer head are provided with extensions 45—45, each of which is formed with a rib 46 which is slidably disposed in the guideway 18 formed by the flanges 17—17 of the channel members 16—16. The buffer head 43 is cut out about the post 42 to provide a recess 146 for the reception of inner and outer springs 47 and 48, the outer spring having its ends bearing upon the inner surface of the buffer head and the forward ends of the friction shoes 35—35, while the spring 48 which is of smaller diameter and disposed within the spring 47, bears upon the inner surface of the buffer head and shoulders 49 of the wedge 38, the springs 47 and 48 being of less capacity than the springs 40—40.

Under the influence of a relatively light shock, the buffer platform 15 will move inwardly, carrying with it the center stem 14, the inner end of which will bear against the buffer head 43 moving the same inwardly with reference to the housing 12, compressing the springs 47 and 48 against the wedge 38 and friction shoes 35—35, and the follower 39, which is resisted by the springs 40—40, the buffer head 43 being guided in this movement by the sliding movement of the ribs 46 in the guides 18 formed by the flanges 17—17 of the channel members. Due to the difference in the capacity of the preliminary springs 47—48 and the main springs 40—40, and the disposition of the members forming the friction system, no action of the friction system will occur, and upon removal of the relatively light pressure from the buffer head 43, the same will resume its initial position under influence of the preliminary springs 47—48. Under the influence of heavier shocks, the buffer head necessarily will move a greater distance, and under these conditions, the movement initially will be against the tension offered by the preliminary springs 47 and 48, and thereafter upon contact of the inner end of the post 42 of the buffer head with the adjacent end of the extension 41 on the wedge, the wedge will be moved rearwardly, imparting movement to the shoes 35—35 both laterally against the friction surfaces of the liners 32—32, and longitudinally against the follower 39 and the main springs 40—40. When pressure is removed from the buffer head 43, release is effected by initial movement of the follower 39 bearing upon the shoes 35—35 which operate upon the wedge and preliminary springs to force the buffer head outwardly to its normal position, outward movement of the buffer head being limited by engagement with the thimbles 23 secured to the rivets 22—22.

While I have herein shown and described what I consider the preferred manner of carrying out the invention, the same is merely

illustrative, and I contemplate all changes and modifications which come within the scope of the claims appended hereto.

I claim:

5. 1. In a buffing mechanism, the combination with a housing having longitudinally extending guides; of a main spring resistance arranged in said housing; a friction system comprising stationary liners secured to said 10 housing, and friction shoes and a wedge co-operating with said shoes, said wedge and shoes being longitudinally movable with reference to said housing, and said friction shoes bearing against said main spring resistance; a buffer head movably mounted in said 15 housing and adapted to engage said wedge after preliminary movement of said buffer head a predetermined distance, said buffer head being provided with guide arms 20 slidably disposed in the longitudinally extending guides of said housing; and preliminary yieldable means interposed between said buffer head and said shoes and wedge and compressible between said buffer head and 25 shoes and wedge for absorbing relatively light shocks prior to engagement of said buffer head and said wedge, after which said friction shoes and wedge are moved longitudinally with reference to said housing against 30 the pressure of said main spring resistance.
2. In a buffing mechanism, the combination with a fabricated housing made up of separate elongated members; means for securing said members together, including a centrally 35 disposed shell, and spacing and securing members arranged at opposite ends of said housing, said shell being provided with interior friction surfaces; a wedge; friction shoes engaged by said wedge, said shoes cooperating 40 with the shell friction surfaces; a main spring resistance disposed in said housing and bearing against the spacing and securing members at one end thereof and against said friction shoes; a buffer head at the opposite end of 45 said housing and adapted to abut against said spacing and securing members at the opposite end of said housing to limit outward movement of said buffer head; and preliminary yieldable means interposed between said 50 buffer head and said wedge and friction shoes and adapted to be compressed against said friction shoes and wedge prior to operative movement of the latter against said main spring resistance.
55. 3. In a buffing mechanism, the combination with a fabricated housing made up of oppositely disposed elongated channel members, the flanges of which are arranged in spaced relation to provide longitudinally extending 60 guides; of means for securing said channel members together including a friction shell, and spacing and securing members arranged at opposite ends of said housing; movable friction means co-operating with the shell; a 65 main spring resistance in said housing inter-
- posed between the friction means and the spacing and securing members at one end of the housing; and a buffer head in said housing adapted to abut against said spacing and securing members at the other end of the 70 housing to limit outward movement of the buffer head, said buffer head being adapted to engage said friction means and move the latter inwardly of the friction shell against the pressure of said main spring resistance, said 75 buffer head being provided with guide arms slidably disposed between the spaced flanges of the channel members.
4. In a buffing mechanism, the combination with a fabricated housing made up of channel members having their flanges disposed in spaced relation to provide guides; of means for securing said channel members in operative position, including a centrally arranged casing rigidly secured to said channel members and having walls spaced from the flanges of said channel members; a buffer head provided with guide arms slidably disposed in said guides and movable between the flanges on said channel members and the adjacent 85 walls of said casing; friction elements co-operating with said shell; a main spring resistance interposed between said friction elements and a fixed portion of said housing; and preliminary springs interposed between 90 said friction elements and said buffer head.
5. In a buffing mechanism, the combination with a fabricated housing made up of channel members having their flanges disposed in spaced relation to provide guides; of means for securing said channel members in operative position including a centrally arranged casing rigidly secured to said channel members and having walls spaced from the flanges of said channel members and other 95 walls secured to webs of said channel members, said other walls, and the webs of said channel members being provided with apertures; oppositely disposed fixed liners in said shell and each having a boss detachably insertable in one set of apertures in said shell and web of the channel members; friction means including friction shoes having surfaces engageable with said liners and a wedge co-acting with said shoes; a buffer head provided with guide arms slidably disposed in said guides; a main spring resistance interposed between said friction means and a fixed portion of said housing; and preliminary 105 springs interposed between said friction 110 means and said buffer head.
6. A housing for buffers made up of channel shaped members having their flanges arranged in spaced relation to provide guides; an integrally formed hollow shell disposed between said channel members and secured thereto for maintaining said members in predetermined spaced position; a plate-like member secured between one set of ends of said channel shaped members and maintain- 125 130

ing the same in spaced relation and providing a wall adapted to withstand pressure; and combined spacing and securing members secured at the opposite set of ends of 5 said channel members and constructed to operate as stops for moving parts adapted to be disposed within said housing.

7. In a buffing mechanism, the combination with a pair of channel members arranged with their flanges in spaced relation to provide guides; means for spacing and securing said channel members in operative position including a centrally disposed hollow shell, certain walls of which are 10 spaced with reference to the flanges of said channel members, and other walls of which are secured to the webs of said channel members; a rear abutment wall secured between the rear walls of said channel members; securing means for the forward walls of said 15 channel members including spacing thimbles; friction elements cooperating with said shell and including friction shoes and a wedge; a buffer head mounted in said housing, forward movement of which is limited by said thimbles, said buffer head being provided with guide arms slidably disposed in said guides; a spring follower having means bearing on the adjacent end portions of said 20 friction-shoes and upon said shell; a main spring resistance interposed between the rear wall of said housing and said spring follower; and preliminary springs interposed 25 between said buffer head and the wedge and friction shoes.

8. In a buffing mechanism, the combination with a housing; of a main spring resistance mounted in said housing; a friction system

arranged centrally within said housing and comprising fixed friction members, each of 40 which has a boss detachably engageable with an aperture in said housing, and a friction surface adapted to co-operate with friction shoes arranged between said wedging surfaces; a wedge co-acting with said friction 45 shoes; a main spring resistance interposed between a fixed portion of the housing at the rear end and said friction system; a buffer head; and preliminary springs interposed 50 between said buffer head and the friction system, said buffer head being adapted to engage said wedge to actuate said friction system after predetermined preliminary movement thereof.

9. In a buffing mechanism, the combination 55 with a rectangular housing made up of opposed channel members, the webs of said channels defining opposed walls of the housing and the flanges of said channels defining the remaining walls of said housing and 60 being disposed in spaced relation to provide guides between their free edges; of spacing means fixed to the channels for securing the parts together, one of said spacing means being in the form of a friction shell; a buffer 65 head provided with guide arms slidably disposed in the guides provided by the flanges of the channel members; and means for resisting movement of said buffer head inwardly 70 of said housing, including friction means co-operating with the shell.

In witness that I claim the foregoing I have hereunto subscribed my name this 29th day of March, 1927.

JOHN F. O'CONNOR.
